CLAIM

The ornamental design for a free-standing grow light, as shown and described.

DESCRIPTION

FIG. 1 is front perspective view of a free-standing grow light, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the free-standing grow light which form no part of the claimed design. A symbolic break is shown in the free-standing grow light, and the appearance of any portion between the break lines forms no part of the claimed design.
